CLAIM

The ornamental design for an oil dispenser, as shown, and described.

DESCRIPTION

FIG. 1 is a perspective view of an oil dispenser, showing our new design;

FIG. 2 is a front elevation view thereof;

FIG. 3 is a rear elevation view thereof;

FIG. 4 is a right side elevation view thereof, the left side elevation view being a mirror image thereof;

FIG. 5 is a top plan view thereof;

FIG. 6 is a bottom plan view thereof; and,

FIG. 7 is a perspective view thereof in a use environment. The broken lines in the drawings represent portions of the oil dispenser that form no part of the claimed design.
